US0D1063818S

(12) **United States Design Patent** (10) Patent No.: **US D1,063,818 S**
 Venugopal et al. (45) Date of Patent: ** Feb. 25, 2025

(54) **BATTERY**(71) Applicant: **GoPro, Inc.**, San Mateo, CA (US)(72) Inventors: **Sameer Mysore Venugopal**, Milpitas, CA (US); **Deepak Kumaar Kandasamy Karthikeyan**, Union City, CA (US); **Juntao Sun**, Shenzhen (CN); **Wei Wang**, Shenzhen (CN)(73) Assignee: **GoPro, Inc.**, San Mateo, CA (US)(***) Term: **15 Years**(21) Appl. No.: **29/817,146**(22) Filed: **Nov. 29, 2021****Related U.S. Application Data**

(63) Continuation of application No. 29/699,944, filed on Jul. 30, 2019, now Pat. No. Des. 940,066, which is a continuation of application No. 29/619,365, filed on Sep. 28, 2017, now Pat. No. Des. 861,592.

CLAIM

The ornamental design for a battery as shown and described.

DESCRIPTION

FIG. 1 is a top, front, left perspective view of an embodiment of a battery.

FIG. 2 is a left elevation view of the battery shown in FIG. 1.

FIG. 3 is a right elevation of the battery shown in FIG. 1.

FIG. 4 is a rear elevation view of the battery shown in FIG. 1.

FIG. 5 is a front elevation view of the battery shown in FIG. 1

FIG. 6 is a top plan view of the battery shown in FIG. 1. FIG. 7 is a bottom plan view of the battery shown in FIG. 1.

FIG. 8 is a top, front, left perspective view of another embodiment of a battery.

FIG. 9 is a left elevation view of the battery shown in FIG. 8.

FIG. 10 is a right elevation of the battery shown in FIG. 8. FIG. 11 is a rear elevation view of the battery shown in FIG. 8.

FIG. 12 is a front elevation view of the battery shown in FIG. 8

FIG. 13 is a top plan view of the battery shown in FIG. 8; and,

FIG. 14 is a bottom plan view of the battery shown in FIG. 8.

The broken lines in the drawings are for the purpose of illustrating portions of the battery and form no part of the claimed design.
